UNITED STATES PATENT OFFICE.

RICHARD M. CHRISTENSEN, OF NEW YORK, N. Y.

WASHCLOTH.

Application filed June 24, 1925. Serial No. 39,198.

To all whom it may concern:

Be it known that I, RICHARD M. CHRISTENSEN, a citizen of the United States, and resident of New York, in the county of Bronx and State of New York, have invented certain new and useful Improvements in Washcloths, of which the following is a specification.

This invention relates to wash cloths, and has for its primary object and purpose to provide a fabric which will have a relatively open texture and comparatively rough surface but capable of retaining or holding a soapy solution so that the cloth may be used both for the application of the detergent and for producing a relatively high friction or scouring effect.

In one practical embodiment of the invention, I attain the above result by the use of sisal hemp which is obtainable in the form of twisted strands of various thicknesses and may be readily woven or interlaced to form a mat or fabric of any desired length or width. In order to prevent the rolling of the fabric upon itself by reason of the nature of the material employed, the interwoven twisted strands are arranged with the twist of adjacent parallel strands extending in relatively opposite directions.

It is a further general object of the invention to provide a combined washing and scouring fabric or cloth of the above character which will be exceedingly durable, and can be cheaply manufactured and sold.

With the above and other objects in view, the invention consists in the improved wash cloth and in the several novel features thereof as will be hereinafter more fully described, illustrated in the accompanying drawing, and subsequently incorporated in the subjoined claims.

In the drawing, wherein I have illustrated a preferred and satisfactory embodiment of the invention, and in which similar reference characters designate corresponding parts throughout the several views,—

Figure 1 is a plan view of a fragment of the cloth or fabric constructed in accordance with my present invention, and

Fig. 2 is a section taken on the line 2—2 of Fig. 1.

Referring in detail to the drawing, the cloth is composed of a good grade of sisal hemp which is procurable in the form of strands of a desired diameter which may be interwoven to produce a cloth or fabric by

means of a suitable loom. As clearly shown in Fig. 1 of the drawing, adjacent spaced strands 5 extending in one direction have the twist of the strand fibers reversely disposed, and similarly, the twist of the adjacent strands 6 extending at right angles to the strands 5 and interwoven therewith is also reversely disposed. While in the drawing I have indicated a certain spacing of the intersecting strands of hemp, it will be understood that said strands may be arranged in closer relationship with each other to thereby reduce the size of the interstices between the intersecting strands and obtain a closer weave. I have found that by interweaving the strands with the twist of the adjacent strands reversely disposed, that the tendency of the fabric to curl or roll upon itself is counteracted so that the fabric will lie perfectly flat.

As is well known, sisal hemp is exceedingly durable, and the fibers thereof present a very rough surface on the hemp strands. Thus, a highly abrasive action is secured and the surface of a wash cloth composed of this fabric may be readily covered with a soapy or detergent solution by a few rapid movements of the soap cake over the surface of the fabric. This detergent solution will be readily retained by the meshes of the fabric and thus when the cloth is applied to the body, the detergent solution is caused to enter the pores of the skin which are opened by the high frictional abrasive action of the rough surface of the cloth on the skin as it is moved thereover. Therefore, with my improved wash cloth, it is unnecessary to use a brush such as is usually employed for this purpose. Of course, it will be understood that such a scouring fabric might also be advantageously employed for various other purposes in addition to its use as a wash cloth.

From the foregoing description, the construction and several advantages of my present invention will be readily understood. It will be seen that such a wash cloth will be exceedingly durable as well as highly serviceable for the purpose in view. It is also obvious that a cloth of this character can be manufactured and sold at small cost. While I have herein shown and described a preferred embodiment of my present improvements, it is nevertheless to be understood that the device is susceptible of certain modifications thereof and I accordingly re-

serve the privilege of adopting all such legitimate changes as may be fairly embodied within the spirit and scope of the invention as claimed.

5 I claim:

1. A wash cloth composed of interwoven twisted strands of hemp fiber, the twist of adjacent parallel strands extending in reverse directions.

2. A wash cloth composed of interwoven ¹⁰ strands of sisal hemp having the fibers of adjacent parallel strands twisted in relatively opposite directions.

In testimony that I claim the foregoing as my invention, I have signed my name ¹⁵ hereto.

RICHARD M. CHRISTENSEN.
